FIGHTING TOY

Albert Deans Fairgrieve, Vancouver, British Columbia, Canada

Application October 2, 1933, Serial No. 691,779

21 Claims.

(Cl. 46—40)

My invention relates to improvements in fighting toys, the objects of which are to provide means whereby a match may be played by two figures representing boxers and the count taken by a referee, as one of the boxers is knocked out; to provide means whereby the boxers are largely controlled by the operators of the toy and whereby either of the boxers may be restored to an upright position subsequent to being knocked partly over in response to manipulation by the operator controlling the boxer who administered the blow which upset the equilibrium of the one.

The invention consists of two figures representing boxers, means for imparting movement to their arms and separate means for moving their legs and for swinging their bodies, which latter means is under selective control of the operators, as will be more fully described in the following specification and shown in the accompanying drawings, in which:

Figure 1 is a plan view of the toy taken immediately below the platform and showing the control rods for the foot and body movement.

Figure 2 is a sectional view taken on the line 25 2—2 of Figure 1.

Figure 3 is a sectional view taken on the line 3—3 of Figure 1, with the drive means operatively connected.

Figure 4 is a similar sectional view showing the 30 drive means disconnected.

Figure 5 is a sectional view of one of the boxers as viewed from the back.

Figure 6 is a sectional view of same as viewed from the side.

35 In the drawings like characters of reference indicate corresponding parts in each figure.

The numeral 1 indicates generally a casing having side walls 2 one of which carries a coin lock 3 of any suitable type which serves to permit 40 the device to be operated. Upon the casing is a platform 4 forming a ring in which the boxers fight. The platform is provided with pairs of slots 5 and 6 indicated in dotted line in Figure 1; these slots are reversely curved and those of each 45 pair are opposed so that leading from the inner end of each pair towards their outer ends they converge, then diverge and finally converge again.

Standing upon the platform are two figures or 50 boxers 7 and 8, both identical in construction, each having legs and feet 9, bodies 10, heads 11 and arms 12 fitted in the usual way with boxing gloves 13. The intersection or joint of the legs and bodies consists of two cams 14 and 15 which 55 may be slightly concavo convex or flat as desired though the former is preferred, different por-

tions of the faces of these cams are at varying angles to the axis X (indicated by chain dotted line) of the legs. The legs are resiliently connected to the body by tension springs 16 surrounding sleeves 17, so that if one or both legs are turned upon the body, by virtue of its cam faces 18 riding upon the cam faces 14, the body swings either forwardly or rearwardly and if one leg is moved forward of the other and both are turned, the body will swing also to some extent sidewise. 10 The feet of each boxer are hingedly connected at the heels as at 18 to the free end of a pair of spring forks 19, which forks are provided with an operating knob 20 and are slidably carried immediately below the platform 4 so that they can be 15 moved in or out or from side to side as desired to dispose the feet of the boxers at any position along the slots 5 or 6.

The heads 11 are each pivotally connected to the body with a downwardly extending flat stem 20 21 and a spring 22. The stem passes through a rectangular slot 23 in the body, so that the head may not twist unduly, though it may by virtue of the spring tension swing freely in any direction.

Mounted non-rotatably but centrally below the platform 4 is a vertical shaft 24 upon which is journaled a disc 25, above the disc is a collar 26 and a spring 27 and above the spring is a vertically slidable plate 28 which is held depressed 30 when the device is in play by a fork 29 which is engaged at its end by a trigger 30 weighted at its outer end as at 31. The fork 29 is mounted upon a shaft 32 having an operating handle 33 extending beyond the end walls of the casing 35 for manual setting, this shaft is provided with a lever 34 which is normally engaged by a projection 35 of the coin lock mechanism 3 which prevents the shaft from being rocked by the handle 33 until a coin is inserted, but subsequently allows the handle to be turned and the fork 29 to be lowered until engaged by the end of the trigger 30, thus holding the plate 28 in depressed position. Slidably supported above the plate 28 is a flange 36 which is adjustably and 40 resiliently depressed below the platform 4 by a spring 37, this flange is provided on opposite sides with eyes 38.

Connecting the toes of each foot of one boxer 50 8 with the crotch of the spring fork 19 controlling the other boxer is a spring wire 39, which passes through one of the eyes 38 and is surrounded adjacent the toe connection with a coil spring 40 which is anchored at its lower end to the wire and is adapted to abut the underside 55

of the platform as the inner end of the wire is drawn upwardly due to the falling of one of the boxers, thus preventing him from falling too heavily on receiving a knock out blow, and 5 to restore him to standing position if he is not knocked over too far. By virtue of spring wire being used for the elements 39 and also the spring 37 serving to depress the flange 36, a resilient force is exerted on the toes of each boxer to hold 10 them in standing position.

A forked arm 41, see Figure 3, is pivotally connected to the underside of the platform 4, which rests its free end upon the flange 36 and is raised or lowered accordingly as the flange 15 moves. Intermediate the length of this arm a cord 42 extends to the trigger 30, so that when one of the boxers is knocked down a strong upward pull is imposed upon one end of the wires 39, thus raising the flange 36 and the forked 20 arm 41, and through the cord 42 the trigger is swung out of abutment with the fork 29, thus allowing said fork and the plate 28 to rise to the position shown in Figure 4, with the assistance of the then freed spring 21.

25 Downwardly extending from the platform 4 are two pairs of brackets 43 and in the free end of each a rocking lever 44 is mounted. Each rocking lever 44 is provided at its outer end with a roller 45 and is connected at its inner end by 30 a wire 46 which passes upwards through a foot and leg 9 and body 10 to a cranked shaft 47 upon which an arm 12 is secured.

Supported above the disc 25 upon uprights 48 is a cam ring 49 having upon its underside a 35 plurality of wedge shaped cams 50 of varying size and inclination, each of which is adapted to progressively engage the rollers 45 of the rocking levers 44 as they pass thereover, thus depressing them and through the slackening of the wires 46 passing upwards through the feet, legs and bodies which connect with the cranked shafts 47 carrying the arms 12, lowering said arms and when the tension springs 51 to the rocking levers 44 rapidly reverse 40 their motion as the rollers 45 disengage each cam 50 the wires 46 are tensioned, thus swinging the arms upwards to administer blows upon the opposing boxer.

50 Mounted upon the platform 4 to the side of the boxers is the figure of a referee 52 whose arms 53 and 54 are swingingly mounted on cranked shafts 55 and are operated through wires 56 and 57. Suspended from the wire 56 is an iron plate or armature 58 to which is attached also a cord 59 extending upwardly and through an eye 60, thence downwardly to the plate 28 to which it is secured. The wire 57 extends downwardly and has suspended from it another iron plate 61 which is adapted to be engaged at intervals of rotation of the disc 25 by a plurality of inverted and inclined horseshoe magnets 62 carried by said disc. Carried by the disc 25 is another magnet 63 which is set to a smaller radius than those of the magnets 62, but at a 55 greater radius than that of the armature 58 when in its normal position as shown in Figure 3. A wheel 64 mounted upon a shaft 65 forms a driving means for rotating the disc 25, but this may be substituted by any manual or motor drive desired.

70 Following a play in which one of the boxers 8 is knocked out, a coin is inserted into the lock and the handle 33 turned to swing the fork 29 downwardly and depress the plate 28 into normal or operating position with the trigger 30 abutting 75 the free end of the fork. The plate 28 prior

to depression was in contact with the inner end of the rocking levers 44 raising them to such an extent as to prevent the engagement of the cams 50 with the rollers 45. The knob 20 remote from the fallen boxer is outwardly drawn, thus through the wires 39 pulling him back into standing position and withdrawing the other boxer 7 back from the centre of the platform 4. The disc 25 and its cam ring 49 are set in rotation and by virtue of the plate 28 having been lowered out of contact with the inner ends of the levers 44 their rollers 45 are set to be engaged by the cams 50, so that as each cam passes a roller the arm connected therewith is swiftly moved in an upward direction to administer a blow to the opponent boxer. Each 10 player, having assumed control of an operating knob 20 moves his fork 19 forwardly or backwardly or from one side to another as he may deem fit to dispose his boxer and the boxer's body in position to most effectively fight the opponent boxer. During this play the magnets 62 in passing in the path of the armature 61 engage it and by so doing exert a pull on the wire 57 and impart an upward movement to the left arm 54 of the referee 52, when the magnet passes beyond the 15 armature of the latter swings free and the tension being removed from the wire 57 the arm 54 drops back to its normal position. When one boxer through manipulation of the corresponding fork 19 and the blow struck by the cam and 20 rocking lever movement knocks his opponent over, the upward pull on the wires 39 due to the toes being raised from the platform 4 compresses the spring 37 and raises the flange 36 and with it the arm 41, this arm, through the cord 42 pulls the trigger 30 free from abutment with the fork 29 and permits the plate 28 to rise into contact with the inner ends of the levers 44, thus preventing them from operating and consequently leaving both boxers at rest. The raising of the 25 plate 28 permits the endwise movement of the cord 59, so that the armature 58 swings outwardly into the path of the magnet 63 to be engaged thereby on each rotation of the disc. Each time that this armature is caught by the magnet 63, the arm 53 is raised, thus simulating the counting 30 out of the fallen boxer by the referee.

What I claim as my invention is:

1. A fighting toy comprising a platform supporting a pair of boxers each having arms, legs and body, means for swinging the arms, and means operable by players for imparting movement to both legs of each boxer causing them to converge or diverge. 50

2. A fighting toy comprising a platform supporting a pair of boxers each having arms, legs and bodies, the bodies being supported solely by the legs, means for swinging the arms, and means operable by players for moving the legs and for swinging the body of each boxer from the hips. 55

3. A fighting toy comprising a platform supporting a pair of boxers each having arms, legs and bodies, means for swinging the arms, means operable by players for moving the legs independently of each other, and means associated with the legs and body of each boxer whereby the turning of either leg with respect to the body, imparts a tilting movement to the body. 60 65

4. In a fighting toy including opposing boxers having legs, arms and bodies, each of said boxers having a joint between the legs and the body in the form of coacting face cams resiliently connected together whereby the turning of one leg with respect to the other imparts a tilting movement to the body. 70 75

5. A fighting toy comprising a platform having pairs of spaced slots, a pair of boxers having feet and legs, arms and a body, each of said feet having a member projecting through one of the slots, said pairs of slots forming tracks for guiding the feet of each of the boxers, means for imparting movement to the arms, and means operable by players engaging said members for moving the boxers feet along the slots simultaneously or one in advance of the other.
10. 6. A fighting toy comprising a platform having a pair of spaced slots, a boxer having a foot movable along each of said slots, and means operable by a player for moving the boxer by exerting force to both feet, said means permitting the advancement of one foot beyond another.
15. 7. A fighting toy comprising a platform having a pair of oppositely curved spaced slots, a boxer having a foot engaging each slot, means connected with the feet operable by a player for moving the boxer along the slots and a pair of opposed cams between each leg and the body, said cams coacting as the boxer moves along the slots for tilting the boxer's body.
20. 8. In a fighting toy having a platform supporting a pair of boxers, means for imparting movement to the boxers' arms, and means operable by players for moving each boxer by the feet, and means causing the feet to spread apart and draw together as the boxer is moved.
25. 9. In a fighting toy having a platform supporting a pair of opposing boxers, means for moving the arms of the boxers, and means operable by two players for moving each of the boxers towards and away from the centre of the platform, a boxer being pivotally connected to each of said player moving means to permit a boxer to fall in response to a blow from the other boxer and means associated with each player moving means for restoring a fallen boxer to his equilibrium.
30. 10. A fighting toy comprising a platform supporting a pair of opposing boxers, means for imparting movement to the boxers' arms, and means operable by opposing players for controlling the position of the boxers upon the platform, a boxer being pivotally connected to each of said position controlling means to permit a boxer to fall in response to a blow from the other boxer, and means as a boxer falls for disconnecting the means for imparting movement to the arms of each boxer.
35. 11. A fighting toy comprising a platform supporting a pair of boxers and a referee, means for moving the arms of the boxers, means operable by opposing players for moving the boxers, said boxers being pivotally connected to members carried by the platform to permit one boxer to fall to a supine position in response to a blow from the other, and means as one boxer falls to the platform for imparting raising and lowering movement to the referee's arm to count out the fallen boxer.
40. 12. A fighting toy comprising a platform supporting a pair of boxers and a referee, means for moving the arms of the boxers, means operable by opposing players for moving the boxers, said boxers being pivotally connected to members carried by the platform to permit one to fall in response to a blow from the other, and means as one boxer falls to the platform for imparting raising and lowering movement to the referee's arm to count out the fallen boxer, said last mentioned means including an armature and a magnet.
45. 13. A fighting toy comprising a platform supporting a pair of boxers, means for moving the arms of the boxers, means operable by opposing players for moving the boxers, said boxers being pivotally connected to members carried by the platform to permit one to fall in response to a blow from the other, the arm moving means consisting of levers and pull cords connected to the arms, and a rotary member having a plurality of tripping devices adapted to progressively engage and release the levers.
50. 14. A fighting toy comprising a platform supporting a pair of boxers, means for moving the arms of the boxers, means operable by opposing players for moving the boxers, said boxers being pivotally connected to members carried by the platform to permit one to fall in response to a blow from the other the arm moving means consisting of levers and pull cords connected to the arms, and a rotary member having a plurality of tripping devices adapted to progressively engage and release the levers, and means as one of the boxers falls for disconnecting said tripping devices from said levers to stop the arm movements.
55. 15. A fighting toy comprising a platform supporting a pair of boxers, means for moving the arms of the boxers, means operable by opposing players for moving the boxers, said boxers being pivotally connected to members carried by the platform to permit one to fall in response to a blow from the other the arm moving means consisting of levers and pull cords connected to the arms, and a rotary member having a plurality of tripping devices adapted to progressively engage and release the levers, and means as one of the boxers falls for disrupting the tripping devices to stop the arm movement, means associated with the boxer moving means for restoring the fallen boxer to standing position, and manually operable means for disconnecting said tripping devices from said levers to stop the arm movements.
60. 16. A fighting toy comprising a platform supporting a pair of boxers, a pair of manually operable forks each having two prongs connected to the heels of a boxer, and a pair of flexible tensioned members extending from each fork to the toes of the boxer connected to the other fork to urge said boxer into a standing position.
65. 17. A fighting toy comprising a platform supporting a pair of boxers, a pair of manually operable forks each having two prongs connected to the heels of a boxer, and a pair of flexible tensioned members extending from each fork to the toes of the boxer connected to the other fork to urge said boxer into a standing position, means for imparting movement to the arms of both boxers, a vertically movable plate connected to the flexible tensioned members and adapted to be raised thereby as one of said boxers falls, and means associated with said plate adapted to disconnect the means for imparting movement to the arms of both boxers as the vertically movable plate is raised.
70. 18. A fighting toy comprising a platform supporting a pair of boxers each capable of being knocked down by the other, and a referee, means for moving the arms of the boxers, means operable by opposing players for moving the boxers and means for imparting movement to one of the referee's arms throughout the entire period of play and for moving the other arm subsequent to the knocking down of one of the boxers.

19. A fighting toy as claimed in claim 18 wherein the referee arm moving means includes an armature and a magnet.
20. A fighting toy comprising a platform supporting a pair of boxers having arms, legs and bodies, means for swinging the arms, means operable manually for turning the legs inwardly or outwardly whereby the body is inclined with respect to said legs, said means comprising converging and diverging slots in which the feet of the boxers are guided as they are moved along the slots.
21. A fighting toy comprising a platform having spaced slots, a pair of boxers having legs and bodies pivotally connected together at each hip, means for moving each of the boxers bodily forward along the slots for advancing one leg in front of the other, and through said advancement causing the body to be inclined in respect to the legs.

ALBERT DEANS FAIRGRIEVE.
